UNITED STATES PATENT OFFICE.

WILLIAM R. GORDON, OF TOLEDO, OHIO, ASSIGNOR TO THE WILLYS-OVERLAND COMPANY, OF TOLEDO, OHIO, A CORPORATION OF OHIO.

RADIATOR.

Application filed July 22, 1918. Serial No. 246,216.

To all whom it may concern:

Be it known that I, WILLIAM R. GORDON, a subject of the King of Great Britain, who have declared my intention to become a citizen of the United States, residing at Toledo, in the county of Lucas, State of Ohio, have invented certain new and useful Improvements in Radiators, of which I declare the following to be a full, clear, and exact description.

My invention relates to improvements in radiators, and more particularly to the construction of the radiator frame or casing, and has for its object to provide improved means for heating the radiator tubes of automobiles and other motor driven vehicles to prevent freezing of the water therein.

A further object of the invention is to provide extensions upon the radiator frame or casing having chambers, in which liquid fuel burning heaters or other suitable heating units are placed, for the purpose of supplying heat to the radiator tubes at such times as it may be found necessary to protect them against excessively low temperatures.

Further objects, and objects relating to economies of manufacture and details of construction, will definitely appear from the detailed description to follow.

I accomplish the objects of my invention by the devices and means described in the following specifications. My invention is clearly defined and pointed out in the appended claims.

A structure constituting a preferred embodiment of my invention is illustrated in the accompanying drawings, forming a part of this specification, in which:

Figure I is a front elevation of a radiator embodying the preferred form of the invention.

Figure II is a side elevation of the radiator shown in Figure I.

Figure III is an enlarged transverse sectional view taken on line III—III of Figure II.

Figure IV is an enlarged horizontal sectional view taken on line IV—IV of Figure III.

Figure V is a sectional elevation taken on line V—V of Figures I, III and IV.

Figure VI is a horizontal sectional view taken on line VI—VI of Figure V.

Figure VII is a horizontal sectional view taken on line VII—VII of Figure V.

In the drawings, similar reference numerals refer to similar parts throughout the several views and the sectional views are taken looking in the direction of the little arrows at the end of the section lines.

In the present invention I have provided a practical and economical arrangement for heating the radiators of automobiles, and one which is particularly advantageous for use on trucks, which are often required, by nature of the work which they perform, to stand at long intervals in the open where they are unprotected from the weather and which are subjected generally to hard usages not accorded other types of automobiles. Cars of this type are often not provided with the usual electrical equipment employed on pleasure cars and, therefore, it is not practical in all cases to heat the radiators by the use of electricity. I have found that it is more satisfactory and economical to provide a liquid fuel burning heater for this purpose than any other form of heating unit, and that the use of kerosene oil affords a very satisfactory fuel which is readily obtainable and comparatively safe to handle.

Referring to the drawings, 10 and 11 represent respectively the upper and lower water circulating heads of the radiator which are connected by the tubes 12 in the usual manner, it being understood that the invention is applicable to various forms of water circulating or cooling systems. Leading from the engine, (not shown) and into the upper head 10, is the pipe 13, and from the lower head 11 the pipe 14 leads back to the engine for conveying the water thereto after it has passed through the tubes 12. The heads 10 and 11 are connected and supported by the side frame members 15, which preferably are channel shaped, and which form, with the heads, a frame or casing in which the circulating tubes are mounted.

The front and back sides of the radiator are normally open, but the front is adapted to be closed by a curtain or shutter 16, when it is desired to protect the tubes against excessively low temperatures to prevent freezing of the water therein. The curtain 16 is mounted upon a spring roller 17 positioned in a casing 18, secured upon the front side of the lower head 11 of the radiator, as shown in Figures I and II. The curtain is provided at suitable intervals along its sides with eyelets 19 adapted to receive the studs 105

or buttons 20, which are correspondingly (spaced) adjacent the inner edges of the upright frame members 15, as shown in Figures I and II. By this means the curtain may be 5 adjusted to any desired height and the opening in the front of the radiator either partially or entirely closed, as the occasion demands.

The radiator is preferably provided at its 10 sides and adjacent the bottom thereof with the extensions 21 which are, in the preferred embodiment of the invention, integral with the upright frame members 15. These 15 extensions comprise box-like casings forming chambers adapted to communicate with the main radiator casing in which the water circulating tubes are mounted. The upper walls of the extensions or casings are each provided with an opening through which is 20 inserted a suitable heating unit 22, the same being in the present instance a liquid fuel burning lamp or heater, such as an oil burning heater, which is removably mounted within the chamber formed by said extension. 25

Upon the bottom walls of each of the extensions are secured the spring catches 23 which are adapted to automatically snap into the annular groove 24, formed on the 30 outer surface of the heater which is provided with the fuel container 25, as shown in Figure V. The front of the cylinder 22 is provided with an opening 26 by which the burner 27 is rendered accessible, as well as 35 the screw cap 28 for closing the fuel inlet opening in the container 25.

The wick 29 of the burner is adjusted by the worm or screw threaded member 30 to regulate the amount of fuel to be burned, 40 said worm being actuated by the operating stem or rod 31 projecting through the deflector plate 32 of the heater, as shown in Figure III. The rod 31 preferably extends through the worm 30 and has its lower end 45 journaled in the plate member 33, while immediately above the worm the rod is journaled in the bracket 34, as shown in Figure V.

At the top of the heater and preferably on 50 the inner face thereof, is pivotally mounted at 55 the shutter for regulating the discharge of the products of combustion accumulating in the heater from time to time, which are adapted to escape through the openings 37 55 in the top 38 of the heater. The shutter is operated by the handle 39 which projects through the annular slot 40 formed in the wall of the heater adjacent the top thereof. The movement of the shutter upon its pivot 60 is limited by the pin 41 which projects into the radial slot 42 formed in the upper end wall 38 of the heater.

Upon the bottom wall of the extension or casing 21 is provided a pin or stud 43, which 65 projects into a recess formed in the bottom

of the heater to prevent the latter from turning when engaged by the spring catches 23.

Upon the front of the extension 21 is provided a door 44 which is hinged at 45 and normally held closed by the latch 46 to cover 70 the opening 47 in the front wall of the extension.

In the rear wall of said extension is provided the openings 48 for venting the heater chamber, said openings being controlled by 75 the shutter 49, pivoted on the support 50, which is suitably connected with the outer face of said wall.

The heaters are adapted to be removed bodily from the chambers in which they are 80 mounted and are likewise insertable therein and automatically locked by the spring catches 23.

Having thus described my invention, what I claim as new and desire to secure by Letters Patent, is:—

1. In combination, a plurality of radiator tubes, a casing for the tubes and a heating unit within said casing having a part for conveying the products of combustion arranged to project outwardly from the casing through an opening in the wall thereof and adapted to substantially close said opening. 90

2. In combination, a radiator, a casing for the radiator having an air inlet opening in the rear thereof, a shutter for regulating the size of said opening, a heating unit within said casing arranged to project through one of the walls thereof, and means for holding said heating unit in said casing. 95

3. In combination, a radiator, a casing for the radiator, a heating unit within said casing arranged to project therefrom, and means exteriorly of the casing for venting the heater. 100

4. In combination, a radiator, a casing for the radiator including extensions on opposite sides thereof forming heating chambers, heating units within said chambers and means for regulating the amount 110 of heat to be supplied to said casing.

5. In combination, a radiator, a casing therefor including an extension thereon forming a heating chamber, a liquid fuel burning heater within said chamber and 115 means for yieldingly holding the heater within the chamber.

6. In combination, a radiator, a casing therefor including an extension thereon forming a heating chamber, a liquid fuel burning heater removably mounted in said chamber arranged to project through an opening in the wall thereof and means upon the wall of the chamber for yieldingly engaging said heater to hold it within the 120 chamber and adapted to release the heater when a pull is exerted thereon.

7. In combination, a radiator, a casing therefor including an extension thereon forming a heating chamber, a liquid fuel 125

- burning heater removably mounted within said chamber, means projecting from the chamber for regulating the supply of fuel to be burned by the heater and a shutter for venting the heating chamber.
8. In combination, a radiator, a casing therefor including an extension thereon forming a heating chamber, a liquid fuel burning heater removably mounted within said chamber arranged to project through and opening in the wall thereof, means exteriorly of the chamber for regulating the supply of fuel to be burned by the heater, a transparent door for said chamber and a shutter controlling an opening in the wall of the heating chamber.
9. In combination, a plurality of radiator tubes, a casing for the tubes having a front opening, an air inlet opening spaced from said front opening, means for regulating the size of said air inlet opening and means for supplying heat to said casing.
10. In combination, a plurality of radiator tubes, a casing for the tubes having a front opening, an air inlet opening spaced from said front opening, means for regulating the size of said air inlet opening and a heater within said casing for supplying heat to said tubes.
11. In combination, a plurality of radiator tubes, a casing for said tubes, means for supplying heat to said casing and a shutter for controlling a supply of air to the casing in rear of the front wall thereof.
12. In combination, a plurality of radiator tubes, a casing for said tubes, means for supplying heat to said casing and means for controlling a supply of air to the casing through the rear wall thereof.
13. In combination, a plurality of radiator tubes, a casing for said tubes provided with heating chambers adapted to supply heat to the casing through openings in the vertical side walls thereof and a heater in each of said chambers.
14. In combination, a plurality of radiator tubes, a casing for the tubes, having lateral extensions forming heating chambers in direct communication with the external surfaces of the tubes, heating units positioned within said chambers and a shutter for venting each of said chambers.
15. In combination, a plurality of radiator tubes, a casing for the tubes, having lateral extensions forming heating chambers in direct communication with external surfaces of the tubes, heating units within said chambers, each provided with a burner and transparent doors in the front walls of said heating chamber opposite said burners.

In testimony whereof, I affix my signature.

WILLIAM R. GORDON.
